UNITED STATES PATENT OFFICE

141,863

DESIGN FOR A SEWING RACK

Robert Gaston Presley, Canton, N. C.

Application March 9, 1945, Serial No. 118,366

Term of patent 14 years

(Cl. D3—19)

To all whom it may concern:

Be it known that I, Robert Gaston Presley, a citizen of the United States, residing at Canton, in the county of Haywood and State of North Carolina, have invented a new, original, and ornamental Design for a Sewing Rack, of which the following is a specification, reference being had to the accompanying drawing, forming part thereof.

The figure on the drawing is a front perspec-

tive view of a sewing rack showing my new design.

The back of the device is flat and without ornamentation.

The drawing is lined for color.

I claim:

The ornamental design for a sewing rack, as shown and described.

R. GASTON PRESLEY.
